CLAIM

We claim the ornamental design for a padel paddle, as shown and described.

DESCRIPTION

FIG. 1 is a front, side perspective view of a padel paddle; FIG. 2 is another front, side perspective view of the paddle of FIG. 1;

FIG. 3 is a front view of the paddle of FIG. 1;

FIG. 4 is a first side view of the paddle of FIG. 1;

FIG. 5 is a top view of the paddle of FIG. 1;

FIG. 6 is a bottom view of the paddle of FIG. 1;

FIG. 7 is an enlarged front perspective view of a central portion of the paddle of FIG. 1; and,

FIG. 8 is a front view of the central portion of the paddle of FIG. 1.

The dashed lines shown in FIGS. 1 through 8 are included for the purpose of illustrating environmental elements only and form no part of the claimed design.
